BY ATTORNEYS.

UNITED STATES PATENT OFFICE

LEGENDRE CINQ-MARS, OF SAN FRANCISCO, CALIFORNIA

FURNACE

Application filed April 1, 1930. Serial No. 440,798.

This invention relates particularly to improvements in hot air furnaces of the gas heated type.

An object of the invention is to provide a gas heated hot air furnace wherein the heated products of combustion move in a substantially uniform path thruout all parts of the casing surrounding the chamber, and the air passing thru the casing and contacting with the members thru which the heated products of combustion flow, is raised to a uniform temperature thruout the entire area of the furnace casing.

A further object of the invention is to increase the area of the parts of the furnace without materially increasing the cost of manufacture, to maintain the products of combustion separate from the air being heated, and to equalize the draft in all circulatory parts of the heater by causing the gases, heat and products of combustion, to travel equal distances from the burner to the point of connection of the heating element with the flue, thru which the products of combustion are discharged to the atmosphere.

A further object of the invention is to increase the efficiency of hot air heaters of the type to be described, thru the use of flues connecting a heating or burner chamber with a collection chamber, thus setting up a circulation of air within the casing surrounding the burner and collection chambers and flues, and exposing a relatively large area of heated surface to the air to be heated that passes thru the casing. The increase in the area of the heated parts is obtained by positioning a collection chamber for the products of combustion, in spaced relation above the burner chamber and connecting both of said chambers by flues or pipes having fins thereon, which are adapted to be heated by conduction, and to thus present a relatively large area of heated surface to the air passing thru the said casing. The arrangement of the collection chamber above the burner chamber, and the connection of the respective chambers together by the heated pipes, provides for a balanced or equalized draft and flow of the products of combustion from the burner chamber to the collection chamber,

due to the fact that the outlet or discharge opening in the collection chamber is in the center of the top thereof, and the products of combustion in passing from the burner chamber to the collection chamber, thru the connecting pipes, must flow an approximate uniform distance in every instance, and eliminates any "short cut" of the products of combustion from the burner chamber to the discharge flue.

Other objects and advantages are to provide a hot air furnace of the gas heated type, that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

In the accompanying one sheet of drawing: Fig. 1 represents a plan section of a furnace with the top of the enclosing casing removed, taken on the line 1—1 of Fig. 2.

Fig. 2 is a vertical cross section of the furnace shown in Fig. 1, taken on the line 2—2 of Fig. 1.

Fig. 3 is a top plan view of a modified form of furnace, taken on the line 3—3 of Fig. 4.

Fig. 4 is a vertical cross section taken thru Fig. 3, on the line 4—4.

Fig. 5 is a cross section taken thru one of the heater pipes, on the line 5—5 of Fig. 2.

Fig. 6 is an enlarged cross section thru a modified form of collection chamber of the type used in Figs. 3 and 4, showing an arrangement of the baffled interior thereof.

Fig. 7 is a vertical section taken thru the collection chamber, in Fig. 3 on the line 7—7.

Fig. 8 is an enlarged section showing the reduced sized opening at the point where the heater pipes are connected to the collection chamber.

In gas heated hot air furnaces it is particularly desirable for an efficient and economical

furnace, that the lineal distance of travel of the products of combustion from the burner chamber thru each heat distributing pipe to the outlet or flue opening, be approximately 5 the same, thus equalizing the draft and causing a better and more efficient heating operation, due to the fact that the burner will burn the fuel evenly and thoroughly under balanced or equalized draft conditions, hence 10 causing the heater parts to be heated uniformly, and providing for a quicker and more thorough heating of the air around said heated parts.

In detail the construction shown in the accompanying drawing consists of an air heating casing 1, having screened air intake openings 2 at the bottom thereof, and a plurality of hot air ducts 3 leading from the upper end thereof. Air admitted to this casing thru 15 the screened openings therein, is heated by a furnace unit consisting of a burner or heater chamber 4, a collection chamber 5 arranged in spaced relation above the burner chamber, and pipes 6 connected at each of 20 the opposite ends thereof, to the burner and collection chambers.

The burner chamber 4 as shown in Figs. 1 and 2 is preferably cylindrical and at equally spaced points around the outside thereof, is 30 provided with outlet openings 7. A gas burner 8 is arranged in the lower part of the burner chamber, said burner having a pipe or pipes 9, connected thereto and extended out thru the outside of the enclosed casing 1. 35 The pipes 9 are encased within a conduit 10 that connects the outer casing 1 to the open side of the burner chamber 4. The mixture of gas and primary air is admitted thru the pipes or pipe 9, to the burner 8, and the secondary air necessary to support combustion, 40 is admitted to the burner chamber 4 thru the conduit 10.

The collection chamber 5 is preferably circular in form and is arranged directly over 45 the burner chamber 4, in spaced relation thereto. The collection chamber 5 is provided with inlet openings 11 arranged in uniform spaced relation around the circumference of said chamber and an opening 12 is 50 provided in the center of the top of said chamber to which a discharge flue 13 for conveying the waste products of combustion to the atmosphere, is provided. The discharge flue 13 might also be arranged on the under 55 side of the collection chamber 5.

Outlet ports 7 on the burner chamber 4 are connected to corresponding inlet ports 11 on the collection chamber 5, by the pipes or conduits 6. Each pipe 6 is formed of a pair of matching plates 15 and 16, in each of which a semi-circular depression 17 is formed, whereby when the two plates are matched together, the matching semi-circular depressions 17 form a circular opening, which is the 65 pipe 6. The matching plates are held to-

gether by welding, so as to form a hermetically sealed pipe. The upper end of each pipe 6 where it is connected to one of the inlet openings in the collection chamber 5, is provided with a reducing annulus 15' thereon, the bore thru said annulus 15' being of lesser diameter or area than the inner diameter or area of the pipe 6. The purpose of the reducing annulus 15' is to retard the flow of the products of combustion from the burner chamber thru the pipes 6 into the collection chamber and to hold back the flow of the products sufficiently to enable said products of combustion to flow uniformly and evenly thru all of the pipes 6 at the same time, before entry into the collection chamber. Without the reducing annulus 15' in the upper end of each of the pipes 6, the area of opening of said pipes is such that the heated products of combustion might flow thru one or two of the pipes 6, to make a "short cut" from the burner chamber to the collection chamber rather than thru all of the pipes uniformly and evenly, and hence to establish an uneven heating area within the furnace.

I have proportioned the openings 7 from the burner chamber into the distributor pipes 6 so that the heated products of combustion cannot favor a flow or travel thru one or two of the pipes in preference to any of the others, but must flow thru all of the pipes 6 evenly and uniformly. The draft set up in the flue 13 is equalized throughout the burner and collection chambers, and connecting pipes, whereby the products of combustion, etc., in passing thru the pipes 6 into the collection chamber, travel the same distance to reach the central outlet 12 connected with the flue. This insures a uniform heating of all parts of the burner chamber, pipes, and collection chamber, and a maximum of heated surface with which the air to be heated can contact, for an efficient and smooth burner operation. The air that passes into contact with the outside of the burner chamber, heating pipes and collection chamber, does not in any way intermingle with the products of combustion which supply the heat to said air to be heated.

In Figs. 1 and 2, the burner and collection chambers are cylindrical in form, and the pipes that connect the respective chambers are arranged outside of the periphery of each of said chambers and in spaced circumferential relation therearound.

In Figs. 3 and 4, I have shown a modified form of heater which operates in substantially the same manner as the form of heater previously described. The heater shown in Figs. 3 and 4 is of rectangular shape in contrast to the circular form of heater shown in Figs. 1 and 2. The modified form of heater consists of an outer casing 31 having a screened air intake 32 at the bottom thereof

and hot air ducts 33 at the top thereof. A burner chamber 34 is provided centrally within the casing 31, and a collection chamber 35 is arranged directly above the burner chamber 34 in spaced relation thereto. The burner and collection chambers are connected together by vertically disposed pipes 36. The burner chamber 34 is provided with pairs of outlet openings 37 arranged at corresponding points along opposite sides thereof, and a similar arrangement of pairs of intake openings 41 is provided along opposite sides of the collection chamber 35. A pair of gas burners 38 are provided at the bottom of the burner chamber 34, said burners being connected by pipes 39 to a source of gas supply. The pipes 39 are enclosed in a conduit 40 connecting the casing 31 to the burner chamber 34. Primary air and gas is admitted thru the pipes 39 to the burner 38, and secondary air is admitted to the burner chamber thru the conduit 40 around said pipes. A flue 42 to discharge the products of combustion to the atmosphere is arranged in the center of the upper side of the collection chamber 35. A reducing annulus 45 is provided in the discharge or upper end of each of the pipes 36 where the same communicate with the collection chamber 35, to retard and hold back the flow of the products of combustion from the burner chamber into and thru the pipes to the collection chamber for the same reason as that heretofore set forth in the preferred form of the invention. The modified form of the invention as described, is provided with two pairs of pipes 36 at corresponding points on each of the opposite sides of the burner chamber 34 and collection chamber 35. The normal air flow of the products of combustion from the burner chamber to the collection chamber would be thru those pipes 36 nearest the discharge flue 42 rather than thru the pipes 36 a greater distance away from the flue 42. In order to prevent this uneven or "short cut" flow of the products of combustion thru the pipes from the burner to the collection chamber, I have provided a horizontally disposed baffle plate 46 in the collection chamber, and a vertically disposed baffle plate 47 between the bottom of the said collection chamber and the under side of the baffle plate 46. The baffle plate 47 is disposed midway between the ends of the collection chamber and separates the pair of pipes 36 at corresponding points on one end of the casing, from the pair of pipes 36 at corresponding points on the other end of the casing. Openings 48 are provided thru the baffle plate 46 at a point midway between each pair of pipes 36 and at points spaced equidistant from the flue 42. Thus, the heated products of combustion passing into the collection chamber from any pair of pipes 36 must travel an equal distance to enter one of the openings 48 in the baffle plate, and after passing thru said openings 48 into the area above the same, must travel an equal distance to enter the discharge flue 42.

A modified form of collection chamber 51 is shown in Fig. 6, wherein four pairs of intake openings for the products of combustion are provided at the bottom of said chamber 51, each pair of openings being separated by a wall 52 which is connected to a baffle plate 53 disposed in a horizontal plane within the casing, said baffle plate 53 being provided with openings 54 disposed therein at a point midway between each pair of intake openings. There are four of these openings 54 thus provided in the baffle plate 53, and the two pairs of openings thus formed are separated by a division wall 55 extending from the upper side of the baffle plate 53 to the under side of the baffle plate 56. The baffle plate 56 is provided with openings 57 therein disposed midway between the openings 54 in the baffle plate, directly below, and said openings 57 are likewise arranged equidistantly from the discharge flue 58. Thus the course of travel of products of combustion admitted to the collection chamber will be the same between the intake openings and discharge flue. The intake openings in the collection chamber and the baffle plate openings therein, are equidistantly spaced from each other and from the discharge flue, whereby the separated quantities of the products of combustion which pass thru the openings of the burner chamber, travel the same distance from said openings from the burner area to the flue outlet opening of the collection chamber. This eliminates accumulation of unburned or waste gas; prevents hot and cold spots in the heater and otherwise provides an efficient and economical air heating apparatus.

Having thus described this invention, what I claim and desire to secure by Letters Patent is:

1. A heater comprising a burner chamber having a plurality of outlet openings, a burner in said chamber from which the outlet openings are substantially equidistantly spaced, a collection chamber having a plurality of groups of intake openings and provided with an outlet opening; a baffle plate interposed in the collection chamber between the groups of intake openings and the outlet opening, said baffle plate having openings therein, one adjacent each group of intake openings, the opening in said baffle being equidistant from the outlet opening, and the intake openings of each group being equidistant from the adjacent opening in the baffle plate; a flue connected with the outlet opening of the collection chamber; a plurality of pipes having intake and discharge openings in registration and in communication with the outlet and intake openings of

the burner and collection chambers respectively.

2. A heater comprising a burner chamber having a plurality of outlet openings, a burner in said chamber from which the outlet openings are substantially equidistantly spaced, a collection chamber having a plurality of groups of intake openings and provided with an outlet opening; a baffle plate 10 interposed in the collection chamber between the groups of intake openings and the outlet opening, said baffle plate having openings therein, one adjacent each group of intake openings, the opening in said baffle being 15 equidistant from the outlet opening, and the intake openings of each group being equidistant from the adjacent opening in the baffle plate; a flue connected with the outlet opening of the collection chamber; a plurality of pipes having intake and discharge 20 openings in registration and in communication with the outlet and intake openings of the burner and collection chambers respectively; and a casing enclosing said burner 25 and collection chambers and connecting pipes having an air inlet at the bottom thereof and an air outlet at the top thereof.

In testimony whereof, I have hereunto set my hand at San Francisco, California, this 30 14th day of March 1930.
